Samuel F. Watson,
ATTORNEY

UNITED STATES PATENT OFFICE.

SAMUEL F. TAPMAN, JR., OF JAMAICA, NEW YORK.

METAL CLIP.

Application filed December 8, 1923. Serial No. 679,324.

The present invention relates to clips for securing metal sheets to supporting frames of buildings and other structures, and is particularly adapted for firmly securing 5 metal sheets to the supporting frames in the construction of roofs and sides of buildings and other structures and to prevent all lateral and other movement of the metal sheets.

The clip comprising the present invention 10 is adapted for firmly securing metal sheets in the manner stated, whether such metal sheets are corrugated, beaded, crimped, or otherwise formed, and sheets of any kind of metal, such as steel, iron, zinc, copper, process metal, etc., for various kinds of structures, including siding, roofing, ceiling, flooring, etc. It is also adapted for firmly securing metal sheets to various forms of supporting members, such as channels, I- 15 beams, angles, T's, etc.

The accompanying drawing illustrates, by way of example, a preferred form of the present invention.

Referring in detail to the drawing, a pur- 25 lin 5 is illustrated as being in the form of an I-beam. A corrugated metal sheet 10 is illustrated as being secured to the purlin by the improved clip comprising the present invention. The middle section 1 of the clip 30 is straight and is provided at or about its center with an integral upward extension illustrated as being in the form of a rivet 7, whose lower portion 9 rests upon the upper surface of the I-beam or purlin 5 and whose shank 8 passes through or is formed integrally with the clip and passes through an opening in the metal sheet 10 forming part 35 of a roof or other structure. When the device is in place, the head 7 is flattened as 40 illustrated in the drawing. One end of the clip is bent downwardly as shown at 3 in the drawing, and then inwardly as shown in the drawing, and thus grasps one of the lateral flanges of the I-beam or purlin 5.

The other end of the clip is bent straight 45 downwardly as shown at 2. The clip is preferably formed of metal that may be bent readily after the clip is in place, as just described and as illustrated in full lines in the drawing. Where the clip is used with an L-beam or channel beam, the end 2 of the clip is allowed to remain in the position shown in full lines at 2 in the drawing. Where the clip is used with a purlin of I-

beam form, however, after the clip is in 55 place, the end 2 of the purlin may be bent upwardly and inwardly to the position shown in dotted lines in the drawing.

It will be observed that by this construc- 60 tion there is a rigid fixed connection between the purlin and the metal sheet 10; also, that where the sheet 10 is arranged in a slanting position, regardless of which way it slants, the clip will prevent the metal sheet from moving upwardly or downwardly; owing to 65 the fact that the clip is preferably fairly narrow, it does not slide laterally on the purlin, particularly when the end 2 is bent to the position shown in dotted lines in the drawing.

The form of clip shown in the drawing 70 may be modified without departing from the present invention, as defined by the appended claims; for example, the angle portion 1 and the hook portion 13 may be 75 lengthened or shortened; the chord of the arch, or the upward extension, of the middle section may be lengthened or shortened, and may be located at any part of the middle section; the rivet portion may be located at any point of the middle section or at any point in the upward extension; the head of the rivet portion may be partly above and partly below the middle section of the clip; the clip may be made of metal 80 of any thickness and width to meet strength requirements; the top of the middle section may be curved to correspond to the curvature of the corrugations of metal plates used; the rivet portion may be formed integrally with or separately from the clip itself; and other changes may be made which 85 will readily occur to those skilled in the art 90 without departing from the invention.

I claim:

1. A metal clip for securing metal sheets in building construction, comprising a right-angled bendable section at one end adapted to be bent under a purlin for securing said clip thereto, a hook at the other end, and an 100 arched middle section provided with a rivet.

2. A metal clip for securing metal sheets in building construction, comprising a right-angled bendable section at one end adapted to be bent under a purlin for securing said clip thereto, a hook at the other end, and an 105 arched middle section provided with a rivet whose shank is above the arch of the middle

section and whose head extends from the interior apex of the arch to the bottom line of the middle section of the clip.

3. A metal clip for securing metal sheets in building construction, comprising a right-angled bendable section at one end having a flat purlin-engaging face adapted to be bent under a purlin for securing said clip thereto,

a hook at the other end, and an arched middle section provided with a rivet whose shank is above the arch of the middle section and whose head extends from the interior apex of the arch to the bottom line of the middle section of the clip. ¹⁰
